UNITED STATES PATENT OFFICE.

HENRY PETER CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE SWITCHING SYSTEM.

1,214,511.

Specification of Letters Patent.

Patented Feb. 6, 1917.

Application filed June 7, 1915. Serial No. 32,694.

To all whom it may concern:

Be it known that I, HENRY PETER CLAUSEN, a citizen of the United States, residing at Mount Vernon, in the county of West Chester and State of New York, have invented certain new and useful Improvements in Telephone Switching Systems, of which the following is a full, clear, concise, and exact description.

10 This invention relates to telephone switching systems, and more particularly to a cord circuit for manual systems.

The object of this invention is to improve the service of manual exchanges by 15 the provision of facilities for enabling the switchboard operator to make accurate observations of lapsed periods of time during which ringing current is applied to the line and during which the lines are actually connected for conversation.

In accordance with the first mentioned feature of this invention, there is provided for each cord circuit a timing device adapted to operate automatically upon the application 25 of ringing current to the called line, and to operate at different intervals an indicating device which will notify the operator that a certain time has lapsed since ringing current has been applied to the 30 called line, thereby enabling her to keep the calling subscriber advised of conditions. Provision is also made for notifying the operator, by the use of the timing device, of a lapsed period of time during which the 35 lines are actually in conversational connection. This is accomplished by the use of switching means operated when the called subscriber answers to restore and restart the timing mechanism and to associate there-

40 with a signaling circuit which will be closed to indicate a period of lapsed time determined by the operator when setting up the connection with the cord circuit.

The timing mechanism may comprise a 45 step-by-step rotating device adapted to be driven at different speeds by interrupters of different characters and controlling circuit closing contacts during the time of one revolution. The speed at which the timing 50 mechanism is driven during the ringing is preferably constant for all cords of one exchange, while the speed at which it is driven during the time that the lines are connected for conversation is predetermined by the

operator in accordance with the class of 55 service of the lines served.

The drawing is a diagram of a circuit and apparatus embodying the features of this invention.

In the drawing, 5 and 6 designate, respectively, calling and called subscribers' telephone lines, each terminating in a jack 7 and having associated with it the usual telephone set and line signal and cutoff relays. A cord circuit, comprising conductors 8 and 9 terminating in plugs 10 and 11, has inserted in its conductors 8 and 9 condensers 12 and 13 for rendering the talking strands opaque to direct current. Supervisory relays 14 and 15, connected in bridge of the 70 conductors 8 and 9 upon the side of the condensers 12 and 13 adjacent the calling line 5, are operated over the calling line, in a manner well known, to control a supervisory signal 16. Supervisory relays 17 75 and 18, connected with the talking strands 8 and 9 upon the side of the condensers 12 and 13 adjacent the called line 6, are operated in a similar manner to control a supervisory signal 19. A source of ringing 80 current, indicated by signs, is adapted to be connected with called line 6 by means of a key 20, although this may be done automatically in a manner well known in the art. An operator's telephone set 21 of 85 well-known form may be connected in bridge of the cord strands 8 and 9 by means of a key 22.

Means are provided as follows for flashing the supervisory lamp 19 at different intervals during ringing, and also during the time that the lines are connected for conversation. A rotatable step-by-step circuit-controlling device 25, actuated by means of a holding magnet 26 and a stepping magnet 95 27, is adapted to close successively contacts 28, 29 and 30 in its rotation to complete circuits from interrupters 31, 32 and 33 for operating the supervisory signal 19, and to close contact 53 when the lines are connected 100 for conversation to operate the signal 19. Interrupting devices 34, 35 and 36 are provided for driving the step-by-step device 25 through one complete revolution at different predetermined rates of speed. When the 105 plug 11 is inserted in the jack 7 of the called line, the supervisory relay 17 will be energized over a circuit including the cord

- strand 9 and the winding of the supervisory relay, associated with the called line, to ground. Relay 17 operating closes its front contact 38 and completes a circuit from battery at 39, through supervisory lamp 19, contact 40 of a relay 41, winding of relay 42, back contact 43 of relay 18, front contact 38 of relay 17 and conductor 44, through winding of the holding magnet 26 to ground.
- 10 Current in this circuit energizes relay 42, closing contacts 45, 46 and 47 and opening contacts 48 and 49, and also energizes holding magnet 26. The operation of magnet 26 draws a holding pawl 70 into engagement with the step-by-step element 25, and closes a contact 51. Upon the closure of the contact 51 there is completed a circuit for the stepping magnet 27, which may be traced from battery at 52 through the winding of 15 the stepping magnet 27, contact 51, a normally closed contact 53, conductor 54, a back contact 55 of relay 41, a back contact 56 of relay 18 and interrupter 34 to ground. Assume that at the instant the plug 11 was inserted into the jack 7 of the called line, ringing current was connected with the called line 6, either by depressing the key 20 or automatically in any one of the well-known ways. This being the case, the operation of 20 the interrupter 34 will cause current impulses to operate the stepping magnet 27 to move the step-by-step element 25 through one complete revolution in a period of time of, say, two minutes. As the step-by-step element 25 is rotated in response to these impulses, a contact arm 60 thereon is brought successively into engagement with the contacts 28, 29 and 30, the time of its engagement with these contacts being forty, eighty 25 and one hundred and twenty seconds respectively. When the contact arm 60 reaches the contact 28, a circuit will be completed from battery 61 through interrupter 31, contact 45 of relay 42, contact 28, contact arm 60 and conductor 62 to a point 63. Current in 30 this path shunts out the supervisory lamp 19 and causes it to flash in accordance with the interruptions of interrupter 31, thus notifying the operator that forty seconds have expired since the application of ringing current to the line. The operator may then notify the calling subscriber that she is calling the desired party. When the contact arm 60 reaches contact point 29, the operator will 35 receive a signal in accordance with the interruptions of interrupter 32 notifying her that eighty seconds have expired since the application of ringing current to the line, and when the arm 60 reaches contact 30 the operator will receive a signal characteristic of interrupter 33 which will notify her that two minutes have expired since the application of ringing current to the line, and it will be her signal to notify the calling subscriber that the called party does not answer.

When the arm 60 of the step-by-step element 25 reaches the contact member 30, it strikes a stop member 65 and also a contact spring 66 and raises the latter to open the contact 53, thereby opening the circuit of the stepping magnet 27 in order to prevent chattering of the stepping magnet armature.

Upon receiving a request for a connection from the calling subscriber, the operator will, before completing connection to the 7b called line, operate one of two keys 69 or 70 for completing a circuit from interrupters 35 and 36 which will be ineffective until the called subscriber has answered. The keys 69 and 70 are preferably of the locking or indicating type having three positions, a way-down non-locking position in which they control contact 71, an intermediate locking position in which they close the circuit to the interrupters 35 and 36, and a 80 normal or non-operated position. Assuming that the step-by-step element has traversed its full cycle without the called party responding and the calling party has requested a recall. The operator will make 85 the recall merely by depressing key 69 or 70 into its way-down position to close the contact 71, thereby short-circuiting the holding magnet causing it to release the step-by-step element 25 which will be returned 90 to normal by a spring or equivalent means. The deenergization of magnet 26 will also open contact 51 so that the stepping magnet will have no circuit until contact 51 is again closed. As soon as key 69 or 70 is released 10c by the operator, however, it will return to its midway or locking position, opening the contact 71 and completing the circuit for the holding magnet 26 previously traced, whereupon the operation of the step-by-step element 25 will be repeated. Should it happen though that the called for subscriber answers his signal by removing his receiver from the switchhook, relay 18 will become 105 energized over a circuit including the wires 110 of line 6. When this occurs, relay 18 will open contacts 43 and 56 and 82 and close contacts 73 and 74. The opening of contact 43 opens the circuit of relay 42 and the holding magnet 26, thereby releasing relay 42 115 and causing the restoration of the step-by-step element 25 to normal position. Relay 42 in releasing its armature opens the contacts 45, 46 and 47, and closes contacts 48 and 49. It will be noted, however, that relay 42 is made slow release by means of a copper sleeve 75 over its core, so that it will not close its contacts 48 and 49 until the step-by-step element has had time to restore to 120 normal position. After both the contacts 48 and 73 are closed, however, by the energization of relay 18 and the deenergization of relay 42, there will be completed a circuit 125 for the relay 41 and the holding magnet 26 from the battery 76 through contact 48 of 130

relay 42, contact 77 of relay 15 and contact 73 of relay 18 over conductor 44. This will cause the energization of relay 41 and the holding magnet 26, thereby restarting the 5 rotation of the step-by-step element 25 at a speed controlled by the interruptions of interrupter 35, assuming that key 69 has been depressed. The circuit for the stepping magnet 27 may be traced from battery at 52 through contacts 51 and 53, conductor 54, contact 78 of relay 41, conductor 79 and contact of key 69 to interrupter 35 and to ground. The interruptions from interrupter 35 will cause the stepping magnet 27 10 to drive the step-by-step element at a speed of, say, one revolution in three minutes. At the end of this period, contact arm 60 will have been brought into engagement with contact member 30, and a circuit will be 15 completed for supervisory lamp 19 including the contact arm 60, contact member 30, contact 49 of relay 42 and an interrupter 80 to ground. The signal given by the lamp in response to the interrupter 80 will notify 20 the operator that the allotted talking period of three minutes has expired, and the operator will notify the calling party to this effect. If the calling party desires to converse longer with the called party, he will 25 notify the operator who will depress either key 69 or 70 into its way-down position, restoring the timing device to normal in the manner hereinbefore described, and restarting it to give a signal at the end of either 30 three or five minutes, depending upon which of the keys, 69 or 70, was last depressed.

It will be noted that when the relay 41 was operated, it completed a locking circuit for itself and the holding magnet through 40 the contact 38 of relay 17 associated with the called line. This is a precautionary measure provided for the purpose of preventing the calling party from restoring and restarting the timing mechanism by operating 45 his switchhook to operate relay 15. The restoration of the subscribers' receivers to their switchhooks will operate the supervisory signals 16 and 19 in the usual manner. Should it happen that the step-by-step 50 element 25 is in a position of partial advancement at this time, the supervisory lamp 19 will be operated over a circuit including a contact 82 of relay 18 and a contact 83 of relay 41.

55 What is claimed is:

1. In a telephone switching system, subscribers' lines terminating in a central office, a link circuit at the central office for interconnecting said lines, a source of signaling current adapted to be connected with the called subscriber's line, a timing mechanism adapted when started to operate for a predetermined time, means actuated upon the connection of the link circuit with the called 60 line to start the timing mechanism, and a

signaling device controlled by and operating at intervals during the operation of the timing mechanism to indicate to the operator that the called subscriber has not answered. 70

2. In a telephone switching system, subscribers' lines terminating in a central office, a link circuit for interconnecting said lines, a source of signaling current adapted to be connected with the called subscriber's line, 75 a step-by-step timing mechanism adapted when started to operate for a predetermined time, an electromagnetic device actuated upon connection of the link circuit with the called line to start the timing mechanism, a signaling device, and a circuit for the signaling device completed upon the advancement of the step-by-step mechanism to predetermined positions to cause the signaling device to furnish signals at stated intervals. 80

3. In a telephone switching system, subscribers' lines terminating in a central office, a link circuit at said central office for interconnecting said lines, supervisory signals associated with the answering and calling 90 ends of said link circuit and controlled over the respective line circuits, a source of ringing current adapted to be connected with the called line, a timing mechanism associated with the calling end of the link circuit and driven at a predetermined rate of speed; and a plurality of branch circuits closed thereby at predetermined intervals and controlling the supervisory signal of this calling end of said link circuit to notify 95 the operator that no response is made by the called subscriber after lapsed periods of time. 100

4. In a telephone switching system, subscribers' lines terminating at a central office, link circuits therat for interconnecting said lines, a source of ringing current at said central office adapted to be connected with a called line upon the connection therewith of said link circuit, a timing mechanism operated automatically upon connection of ringing current with said line and embracing a rotatable contact member adapted to be driven through a complete revolution in a given interval of time, contacts closed successively by said rotatable member during its movement, a characteristic source of interrupted current individual to each of said contacts, and a signal adapted to be separately operated by the several interrupters 105 for indicating different periods of lapsed time from the application of ringing current to the line. 110

5. In a telephone exchange system, subscribers' lines terminating at a central office, link circuits at said central office for interconnecting said lines, a source of ringing current adapted to be connected with the called line upon the connection therewith of a link circuit, timing mechanism operated 115 120 125 130

during the time that ringing current is connected with the called line, a signal operated by said timing device at predetermined intervals of a given period to indicate that 5 the called subscriber has not answered, switching means adapted to be operated when the called subscriber answers to restore and restart said timing device, and a circuit for said signal completed by said timing device after the lapse of a period of time to 10 indicate to the operator that the lines have been connected for conversation for a predetermined allowable time.

6. In a telephone switching system, subscribers' lines terminating in a central office, 15 a link circuit at said central office for interconnecting said subscribers' lines, a source of ringing current adapted to be connected with the calling line, a signal, a plurality 20 of normally open branch circuits including interrupters of different characters and said signal, a circuit closing element adapted to close said branch circuits successively, means for driving said circuit closing element at 25 a predetermined rate of speed during the connection of ringing current with the line, means controlled from the called subscriber's station for resetting said circuit closing element upon the response of the called subscriber, 30 means for driving said circuit closing element at a different rate of speed when the lines are connected for conversation, said means being rendered effective upon the response of the called subscriber,

and a circuit for said signal closed by said 35 circuit closing element after the lapse of a period of time determined by said second connected driving means.

7. In a telephone switching system, calling and called subscribers' lines terminating 40 at a central office, a link circuit at the central office for interconnecting said lines, supervisory signals associated with the answering and calling ends of said link circuit, 45 relays for each of said signals controlled over the subscribers' lines, a source of ringing current adapted to be connected with the called subscriber's line, a circuit closing element, a circuit for the supervisory signal associated with the calling end of the cord 50 circuit adapted to be closed by said circuit closing element, interrupters for driving said circuit closing element at different speeds, circuit connections controlled in one position of a supervisory relay associated 55 with the calling end of said link circuit for causing said circuit closing element to be driven from one of said interrupters, circuit connections controlled in another position of said supervisory relay to restore said circuit closing element to normal and restart it from a different speed interrupter, and circuits for said supervisory signal closed by 60 said circuit controlling device.

In witness whereof, I hereunto subscribe 65 my name this 3rd day of June A. D., 1915.

HENRY PETER CLAUSEN.
